UNITED STATES PATENT OFFICE.

JOHN L. McMILLAN, OF SYRACUSE, NEW YORK.

LOOSE-LEAF BINDER.

No. 910,714.

Specification of Letters Patent.

Patented Jan. 26, 1909.

Application filed October 28, 1907. Serial No. 399,431.

To all whom it may concern:

Be it known that I, JOHN L. McMILLAN, a citizen of the United States, residing at Syracuse, in the county of Onondaga and State of New York, have invented certain new and useful Improvements in Loose-Leaf Binders, of which the following is a specification.

My invention relates to loose-leaf binders, and the invention consists in various novel features and details hereinafter set forth, the objects of the invention being to produce a binder which shall be at once simple and strong; into which leaves may be inserted and from which they may be removed, readily, during the making up of the book, as where pages are written and inserted; and which may subsequently be converted into a permanent binder if desired.

20 In some of its features the binder resembles that set forth in Letters Patent No. 708,065, granted to me under date September 2nd, 1902, notably in the matter of converting the temporary into a permanent binder.

The invention is illustrated in the accompanying drawings, in which:

Figure 1 is a perspective view of my improved binder with portions broken away to better show details of construction; Fig. 2 is a sectional view taken through the back of the binder; Fig. 3 a view illustrating the mode of opening the binder; Fig. 4 a similar view showing the manner of closing the binder; Fig. 5 a detail showing the manner of locking the binder closed; Fig. 6 a longitudinal section through a portion of one of the rod barrels showing the locking rod in its locking position; Fig. 7 a perspective view of the locking rod; and Fig. 8 a sectional view on the line x—x of Fig. 2, illustrating one mode of uniting the metal and binder's board of the back.

Specific details of construction may be varied considerably without departing from the spirit of my invention, but in the accompanying drawings I have shown an embodiment which gives very satisfactory results, and is the preferred form.

50 In these drawings A indicates a sheet metal back-plate of curving or trough shape, the longitudinal edges of which are fastened into tubular barrels a provided at intervals with notches or recesses b. In these barrels are seated rods, B, C, of cylindrical form in

cross section, and each laterally bent at one end to form a finger-piece c, as shown in Fig. 1.

D indicates an impaling bar or leaf-carrying member, of which three are shown in the drawing. The number may, however, vary as desired, though two at least should ordinarily be used. These bars or members D are slightly curved in the direction of their length to correspond approximately to the curve described by the outer or front edges of the leaves of a bound book. Each bar is provided at one end with an eye e, and at the opposite end with a second eye f, both of which are preferably slotted at one side to make a contracted mouth or opening to the surface of the bar, as shown in Figs. 1, 2, 3, 4, 5 and 7, though it is not essential that the eyes at both ends of the bar or member D be thus slotted. It will be sufficient in some cases to slot the eyes of one end only, and to employ but one rod with the flattened or reduced portions d, the leaves being removed and replaced over the same end of each bar or member D.

When the binder is used for record sheets or leaves, designed to constitute record books, it is found advantageous to supply the binder in the first instance with its full quota of leaves or sheets; to provide a distinctive leaf at the back; and to remove the leaves or sheets one at a time from the front, type-write thereon the desired record matter, and then apply it to the binder at the back, repeating this operation until the first type-written sheet finally returns to the front. In other words, the leaves are consecutively removed from the front and reentered at the back until the entire series having been thus transferred, the leaves fall in regular sequence or numerical order from front to back in their printed form as they were in their original or blank form.

Where this is desired, both the rods B and C will be provided with the reduced portions d, and the impaling bars or leaf-carrying members D will have the open or slotted eyes at both ends. When, however, this mode of handling the leaves is not deemed desirable, and it is for any reason preferred to gradually build up the volume by inserting the leaves in their numerical order from the rear toward the forward side of the binder, it will be sufficient to provide the open eyes only at that end of the bars or members D connected with

the barrel at the rear side of the binder; but as the rod with the reduced portions will serve equally well as a hinge rod under such conditions, it is deemed preferable to provide 5 both rods with the reduced portions, and to slot the eyes at both ends of the leaf-carrying members, in any and all cases, though feasible, as stated, to provide for connecting and disconnecting at one end only of the bars D.

10 The slots or lateral openings of the eyes *e*, *f*, are preferably beveled or widened toward the outer side to facilitate the introduction of the flattened or reduced portions *d* of the rods B and C. When it is desired to connect 15 or disconnect the impaling bars or members D to or from the back A, one or the other of the rods B, C, is moved longitudinally to bring the reduced portions *d* opposite or into the open spaces *b* of the back A, and is then 20 rotated to bring said reduced portions edge-wise with reference to the lateral openings of the eyes of the bars or impaling members D, as indicated in Figs. 3 and 4. In this position said reduced portions may be freely 25 moved into or out of the eyes.

In order to prevent the accidental withdrawal of the rod, it may be turned a quarter revolution, more or less, so that the major axes of the reduced portions *d* shall stand 30 cross-wise of, or at right angles to, the open mouths of the eyes of bars D, as shown in Fig. 5. In lieu of, or in addition to such rotation, the rod may be moved longitudinally so as to carry the reduced portions *d* out of 35 register with the openings *b*, and the portions of full diameter into said spaces. The diameter of the rod being greater than the width of the mouths or openings of the eyes, it will, of course, be impossible for the parts to separate 40 rate while the rod is in such adjustment.

It will thus be seen that if the reduced portions *d* be kept in proper angular relation to the eyes to enter and pass out through the slotted or open sides thereof, it will be sufficient, in order to release or to unlock the impaling bars or leaf-carrying members D, to simply move the rods lengthwise a short distance, but that if the rods be also turned a double lock will be provided which will guard 50 against the accidental detachment of the impaling members, even though the rod be moved longitudinally a considerable distance. It will likewise be observed that it is unnecessary in any case to withdraw the rod entirely from the barrel, or to move it more than a short distance in the direction of its length.

It will be seen that whichever rod be moved to unlock or release the bars or impaling members D, the other rod will, for the time, serve as a hinge pin on which said members, or the back A, may swing or move to effect a separation of the unlocked ends from the binder.

65 The back A, which is advisably curved to

the form of ordinary book-cover backs, is joined by integral tongues *g*, by eyelets *h*, or other suitable fastenings, to a correspondingly curved strip E of binder's board, as best shown in Figs. 2 and 3, but any convenient 70 mode of attachment may be adopted. This strip E serves as a convenient body to which to attach the leather, cloth, or other material constituting the surface of the binder, and it also affords suitable support for the hubs or 75 projecting ribs usual to the backs of heavy books, particularly books of record and the like.

Preferably passing between the curved metal back A and the binder's board strip E, 80 is a strip or sheet F of woven material, usually some strong linen fabric, which is carried between an inner part *i* and an outer part *j* jointly constituting a cover board G, there being, of course, two such cover boards one 85 at either side of the back A. In practice I prefer also to employ a second strip or sheet H of woven fabric, or like flexible material, carrying the same over the back strip E, and thence past the barrels *a* of the curved metal 90 back A, and between the parts *i*, *j*, constituting the cover board G. This construction is well illustrated in Fig. 2. The fabric serves to produce a strong flexible connection between the back and the cover boards. The 95 usual cover or facing I of leather, binder's cloth, or the like, is carried over the back A, E, and glued or otherwise fastened to the back strip E and cover boards G, and this may be extended entirely over the cover 100 board, or separate pieces may be used, according to the style of binding, whether full cloth, full leather, half leather, or the like.

The outer part *j* of the cover boards is stopped at some little distance from the barrels *a* of the back A, as shown in Fig. 2, thus producing the shoulder usual in such bindings. The cloth strips F and H and the covering I are carried over the back strip E, and the strips F, H, are then carried between the 105 cover boards *i*, *j*, while the covering I is carried over the shoulder, and to the outer surface of board *j*.

The manner of converting the binder from a temporary into a permanent one is the same as in the patent before mentioned; that is to say, each rod B and C has a circumferential notch *k* formed a short distance in from the end bearing the finger-piece *c* to facilitate breaking off of the end of the rod 115 when the binder has been completely filled, and no further occasion exists for permitting removal of a leaf or leaves. When this condition is reached, the rod is drawn out until the notch or weakening groove *k* is out of or slightly beyond the end of the barrel *a*, when a sharp lateral bend will cause the rod to break off. It is then pushed inward until the new formed end passes a spur *l* formed in 125 the barrel *a*, which spur is then pressed in- 130

ward by means of any suitable pointed instrument so that its end lies across the interior of the barrel, and precludes the longitudinal movement of the rod. A like spur engages the opposite end. A drop of solder 5 may also be employed to prevent the spur *l* from being bent outward, and the rod being thereby made free to be withdrawn. This, however, constitutes no part of the present 10 invention, and is described merely for the purpose of making clear the full utility of the present structure, the groove or weakening line serving a useful purpose in indicating the point to which the rod shall be withdrawn in 15 order to bring the reduced portions *d* opposite the recesses or openings *b* of the barrel *a*.

It will be observed that under this construction it is unnecessary to withdraw the rods, or either of them, entirely from the barrels 20 in order to connect and disconnect the binding bars or members *D*, but that a quite limited movement longitudinally is sufficient, and that it is possible even to dispense entirely with the longitudinal movement and 25 rely solely upon the rotation of the rod to effect a locking and unlocking. Because of the stronger lock afforded by the longitudinal movement, and the bringing of the full diameter of the rod within the barrel, it is preferred 30 to provide such longitudinal movement.

As indicated in the drawings, the reduced portions *d* of the rod *C* join the portions of full diameter by beveled or inclined faces, so 35 that shoulders are avoided which might, if present, interfere with the free longitudinal movement of the rod through the eyes *f*. The outer mouths of the slotted eyes *f* are preferably beveled to facilitate entering the 40 reduced portions of the rod *C*.

While both on account of its greater strength and simplicity of construction, it is preferred to form the barrels *a* integral with the back *A*, this is not essential, the material 45 point being that the barrels be located at or about the junction of the back and cover boards.

Having thus described my invention, what I claim is:

50 1. In a binder, the combination with a back and cover boards, of impaling bars or members, hinged at one end at a point near the union of the back and one of the cover boards, and having open-sided eyes at the 55 opposite end; and a locking rod located near the junction of the back and the second cover board, and having reduced portions to enter through the slots into the eyes of the impaling bars.

60 2. In combination with a suitable back and cover boards, leaf-carrying or impaling members pivotally connected at one end to the binder at or about the junction of the back and one of the cover boards, and provided 65 at their opposite ends with eyes;

and a locking rod adapted when in one position to freely enter said eyes, and when in different position to lock the leaf-carrying or impaling strips to the binder.

3. In a loose-leaf binder, the combination 70 of a back and cover boards; tubular barrels located at or near the junction of the cover boards and the back, and provided with notches or openings; leaf-carrying or impaling members having perforated ends adapted 75 to fit the notches of said barrels, the eyes at one end having narrow slots or openings extending to the surface of the leaf-carrying member; rods seated in said barrels and adapted to pass through the eyes of the 80 leaf-carrying members, one of said rods being adapted to carry locking portions of the rod into or out of the eyes of the leaf-carrying members through a short longitudinal movement of the rod, and without bodily 85 withdrawing the rod beyond the notches in the barrels.

4. In a loose-leaf binder, the combination 90 with a suitable back and with tubular barrels at opposite edges of such back, provided with notches or recesses; leaf-carrying members of a size to extend from barrel to barrel, and to fit within the notches or recesses therein, the ends of said members being provided with perforations co-axial 95 with the barrels, the perforations at one end having lateral slots or openings to the surface; rods contained within the barrels and passing through the eyes of the leaf-carrying members, one of said rods having reduced 100 portions adapted to be brought, through the partial rotation of the rod, into position to pass through the slots or openings into the open eyes of the leaf-carrying members, and by further, or reverse rotation, to be so 105 positioned as to prevent withdrawal from said eyes.

5. In a loose-leaf binder, the combination 110 of a back having notched and tubular barrels at its opposite edges; leaf-carrying or impaling members hinged at one end to one of said barrels, and provided at the opposite end with eyes having narrow-mouthed slots or openings extending to the surface; and a rod seated in the barrel which receives the free ends of 115 the leaf-carrying members, said rod being rotatable and having flattened or reduced portions, which in one angular position of the rod may freely enter the open eyes of the leaf-carrying members, but which under 120 a different angular adjustment of the rods are held within and prevented from escaping from said eyes.

6. The herein described binder, comprising 125 a back *A* provided with tubular barrels *a* having notches *b*; leaf-carrying or impaling members *D* adapted to reach from barrel to barrel and to enter the notches *b*, said members *D* being provided at their ends with slotted eyes; rod *B* seated within one of the 130

barrels *a* and passing through the eyes at one end of the members *D*; rod *C* passing through the other barrel *a* and provided with reduced portions *d*, said rod *C* being free to rotate within the barrels to bring the reduced portions *d* edgewise to the slotted eyes, or cross-wise thereto as required.

7. In a loose-leaf binder, the combination of a back *A*, tubular barrels *a* at opposite edges thereof provided with notches *b*; leaf-carrying members *D* provided at opposite ends with eyes, those at one end being slotted; a rod *B* seated in one of the barrels *a* and passing through the eyes of the leaf-carrying members *D* inserted in the notches thereof; and a rod *C* seated in the other of said barrels, provided with reduced portions *d*, and adapted both to be rotated

and to be moved longitudinally within the barrels, substantially as set forth. 20

8. The herein described loose-leaf binder comprising back *A* provided with barrels *a* having notches *b*; hinge rod *B* and locking rod *C*; leaf-carrying members *D*; back strip *E* secured to the back *A*; cover boards *G* 25 comprising inner and outer parts *i*, *j*; and a flexible strip extending from the back *A* to the cover boards and secured thereto.

In testimony whereof I have signed my name to this specification in the presence 30 of two subscribing witnesses.
